UNITED STATES PATENT OFFICE.

ROBT. C. WERNER, OF MONACA, PENNSYLVANIA, ASSIGNOR TO THE PHOENIX
GLASS COMPANY, OF MONACA, PENNSYLVANIA, A CORPORATION OF WEST VIR-GINIA.

DESIGN FOR A LAMP.

Application filed June 15, 1925. Serial No. 13,788. Term of patent 7 years.

To all whom it may concern:

Be it known that I, ROBERT C. WERNER, a citizen of the United States, residing at Monaca, in the county of Beaver, State of Pennsylvania, have invented a new, original, and ornamental Design for a Lamp, of which the following is a specification, reference being had to the accompanying drawing, forming a part thereof.

The figure is an elevational view of a lamp embodying my design.

I claim:

The ornamental design for a lamp, as shown.

ROBT. C. WERNER.
